UNITED STATES PATENT OFFICE.

GEORGE W. CROSS, OF PITTSTON, PENNSYLVANIA.

SEPARATOR.

SPECIFICATION forming part of Letters Patent No. 570,460, dated November 3, 1896.

Application filed March 12, 1896. Serial No. 582,878. (No model.)

To all whom it may concern:

Be it known that I, GEORGE W. CROSS, a citizen of the United States, residing at Pittston, in the county of Luzerne and State of Pennsylvania, have invented a certain new and useful Improvement in Separators, of which the following is a specification.

The invention concerns mechanism for separating various materials, such as coal, ore, stone, &c., into various qualities or grades. It relates particularly to that type of separators in which water is employed, the same being passed through the apparatus under pressure.

The object is to provide a durable and efficient device in which the separating operation may be carried on continuously, the different grades or qualities being removed independently.

The invention is designed particularly for use in the separation of slate from coal. This has heretofore been accomplished with the aid of water, which so acts upon the composite material as to separate the slate and coal to some extent. These separators have been found unreliable, the coal being passed therefrom with a considerable admixture of slate, which in the present invention is avoided.

In carrying out my invention I employ a box or case supplied with water under pressure. Within this box or case are located screens or perforate ways through which the water passes freely. The combined coal and slate fed upon these screens is separated by the action of the water, both being passed out of the separator continuously and independently. I have found that by the use of this apparatus no coal is wasted by being passed out of the separator with the slate, and, on the other hand, the quality of the coal from which all slate has been removed is considerably higher.

In the drawings, Figure 1 is a top view of the improved separator, a portion of the hopper through which the coal is fed being, for clearness of illustration, removed; and Fig. 2 is a vertical longitudinal section on the line 2-2, Fig. 1.

Referring to said drawings, A designates the box or case of the separator, which, in the present instance, is rectangular in form and which may be constructed of any desired ma-

terial. This case is provided with the transverse partitions *a a'*, which may be secured to the sides *a²* in any suitable manner.

55

B designates a water-supply pipe by means of which water is conducted to the interior of the separator. *B'* indicates a plunger consisting of the head *b* and its actuating-rod *b'*. The head *b* may, if desired, be provided with a valve or valves (not shown) to permit access of water through the plunger to the interior of the separator and at the same time prevent its egress through said plunger. By suitable power connections the plunger *B'* is given vertical movement, so as to force the water through the separator by intermittent pressure.

C designates an inclined perforate way or screen, the upper imperforate end *c* of which is, in the present instance, supported by means of the partitions *a a'*. It may, if desired, have additional supports in the sides *a²* of the case. The lower end of the screen, which may be supported upon the end *a³* of the case, is depressed at *c'* and is provided with the imperforate portions *c² c'*, the purpose of which will be hereinafter described.

D designates the hopper through which coal is introduced, and, as here shown, I prefer to combine with this an inclined chute *D'*, adapted to receive the coal and to convey the same from the separator to a suitable receptacle. The chute *D'* may be perforated at *d* to drain the coal as it passes over such perforated portion.

E designates a guide-partition suitably supported and having its upper end located adjacent to the edge of the chute *D'*.

F designates a partition supported by the sides *a²* of the case and perforated throughout the whole or a part of its length. *F'* designates an imperforate partition, which may be also supported by the sides *a²*, and which, with the end *a³*, forms a passage for slate. By making this partition with perforations, as explained, the water may pass through the same and form a current between said partition *F* and the imperforate partition *F'*. By this means the composite material will be more fully separated, as will be explained. This partition *F* also serves to direct the flow of coal that may take place between the same and the imperforate parti-

tion F', whereby the coal will be maintained in that portion of the water at that locality where the flow is strongest. Were it not for this partition any coal which might be carried up from the lower end of the partition C might be affected by any currents which might form between the partitions E and F', so as not to be carried out through the discharge.

- 10 In operation the composite material fed through the hopper D falls upon the imperforate portion c of the screen C and passes downward upon said screen. The water which permeates the mass separates, by the 15 intermittent pressure, the coal from the slate, the former being passed along the upper side of the partition E and thence into the chute D', the slate sliding downwardly on the screen. Should there remain in this slate any admixture of coal, a further separation takes place 20 when the mass reaches the imperforate portion c^2 , the remaining particles of coal passing up to the right of the perforate partition F (the separating process continuing through 25 such passage, being assisted by the water flowing through said partition and the slate falling to the bottom) and thence to the coal-chute D', the slate passing on into the depression c' . The flow of water that passes 30 through the perforate partition extends toward the lower end of the second partition, turns sharply, and passes immediately to the discharge. A part of this flow is downward in the direction of the movement of the material, so that the water first passes through 35 the material, so as to bring the coal to the top, and then drives the coal toward the lower end of the second partition, around which it moves, and then passes immediately to the 40 discharge. That portion of the flow which passes through the inclined partition below the lower end of the second partition passes almost in a straight line toward the discharge, so as to assist in carrying the coal around 45 the lower end of the second partition. The slate accumulating in this depression is, by the pressure of the water, passed upward between the end a^3 of the case and the imperforate partition F' and out of the separator 50 by way of the inclined apron G, by means of which the slate may be guided to a suitable receptacle. The apron G may be perforated at g , so as to drain the slate, the water passing therefrom through the gutter g' and pipe 55 g^2 . If desired, the end a^3 of the case may be provided with the gate a^4 , having vertical adjustment.

Should the water-pressure through the perforations in the depression c' become too 60 great, the same may be reduced by means of the hinged adjustable leaf c^4 . Thus, as will be seen, from the time the mixed coal and slate is fed into the hopper until it passes out in the chute the separating operation is being 65 continuously carried on.

What I claim is—

1. In a separator, the combination with a receptacle, a source of water supply communicating with the interior thereof, means for passing the water through the receptacle 70 under pressure, an inclined perforate way in said receptacle, means for feeding upon the upper part of said way the material to be treated, a guide-partition located in said receptacle above said inclined way and inclined 75 in substantially the same general direction, a discharge at the upper end of said guide-partition for receiving a part of the material separated, and another discharge from said receptacle for the remainder of the material 80 separated, substantially as set forth.

2. In a separator, the combination with a receptacle, of a source of water supply communicating with the interior thereof, means for passing the water through the receptacle 85 under pressure, an inclined perforate way in said receptacle means for feeding upon the upper end of said perforate way the material to be treated, a guide-partition in said receptacle above said perforate way and inclined 90 in substantially the same general direction, a chute at the upper end of said guide-partition for receiving a part of the material separated, and a discharge from said receptacle for the remainder of the material separated, 95 substantially as set forth.

3. In a separator, the combination with a receptacle, of a source of water supply communicating with the interior thereof, means for passing the water through the receptacle 100 under pressure, an inclined perforate way in said receptacle, a guide-partition in said receptacle above said perforate way and inclined in substantially the same general direction, a chute at the upper end of said 105 guide-partition for receiving a part of the material separated, and an approximately vertical imperforate partition arranged in said receptacle, with its lower end adjacent to the lower end of said perforate way and between which and the end of the receptacle is formed a passage for the discharge of the remainder of the material separated, substantially as set forth.

4. In a separator, the combination with a 115 receptacle, of a source of water supply communicating with the interior thereof, means for passing the water through the receptacle under pressure, an inclined perforate way above said receptacle, a guide-partition in 120 said receptacle above said perforate way and inclined in substantially the same general direction, a chute at the upper end of said guide-partition for receiving a part of the material separated, an imperforate partition in said 125 receptacle forming between the same and the end of the receptacle a passage for the discharge of the material separated, and a perforate partition in said receptacle located between said guide-partition and the imperforate partition, substantially as set forth.

5. In a separator, the combination with a

receptacle, of a source of water supply communicating with the interior thereof, means for passing the water through the receptacle under pressure, an inclined perforate way in 5 said receptacle, a guide-partition in said receptacle above said perforate way and inclined in substantially the same general direction, a chute at the upper end of said guide-partition for receiving a part of the material 10 separated, an imperforate partition in said receptacle between which and the end of the receptacle is formed a passage for the discharge of the material separated, and a perforate pocket in the lower end of said perforate way 15 in which the heavier material accumulates before being discharged through said passage, substantially as set forth.

6. In a separator, the combination with a receptacle, of a source of water supply communicating with the interior thereof, means 20 for passing the water through the receptacle under pressure, an inclined perforate way in said receptacle, a guide-partition in said receptacle above said perforate way and inclined in substantially the same general direction, a chute at the upper end of said guide-partition for receiving a part of the material 25 separated, an imperforate partition in said receptacle between which and the end of the receptacle is formed a passage for the discharge 30 of the material separated, a perforate pocket in the lower end of said perforate way in which the heavier material accumulates before being discharged through said passage, 35 and means for varying the discharge through

50 said perforate pocket, substantially as set forth.

7. In a separator, the combination with a receptacle, of a source of water supply communicating with the interior thereof, means 40 for passing the water through the receptacle under pressure, an inclined perforate way in said receptacle, a guide-partition above said perforate way and inclined in substantially the same general direction, a chute at the 45 upper end of said guide-partition for receiving a part of the material separated, and drainage-openings in said chute for draining the material discharged into the same, substantially as set forth. 50

8. In a separator, the combination with a receptacle, of a source of water supply communicating with the interior thereof, means for passing the water through the receptacle under pressure, an inclined perforate way in 55 said receptacle, a guide-partition in said receptacle above said perforate way and inclined in substantially the same general direction, means at the upper end of said guide-partition for receiving a part of the material 60 separated, a discharge-chute for receiving the remainder of the material separated, and means for draining the material discharged through said chute, substantially as set forth.

This specification signed and witnessed this 65
28th day of February, 1896.
